UNITED STATES PATENT OFFICE.

WATSON HURLBURT, OF CHICAGO, ILLINOIS.

PACKAGE-HANDLE.

1,109,290.

Specification of Letters Patent.

Patented Sept. 1, 1914.

Application filed December 9, 1908. Serial No. 466,695.

To all whom it may concern:

Be it known that I, WATSON HURLBURT, a citizen of the United States, and residing at 2875 North Forty-ninth avenue, Chicago, in the county of Cook and State of Illinois, have invented certain new and useful Improvements in Package-Handles; and I do declare the following to be a full, clear, and exact description of the invention, such as will enable others skilled in the art to which it appertains to make and use the same, reference being had to the accompanying drawings, and to the letters of reference marked thereon, which form a part of this specification.

The object of the improvement is to do away with the necessity of tying a knot in the binding string of a bundle, thus saving much time, and when wishing to open the package this is easily accomplished without the difficulty of untying knots, hunting for a knife or shears to cut the string.

The invention is illustrated in the accompanying drawings in which—

Figure 1 is a perspective view of a package bound by a cord and fastened with my improved tie embodied with the handle. Fig. 2 represents on an enlarged scale, a carrying handle with my improved tie, the string being shown in dotted lines, a portion of the handle being broken away. Fig. 3 is a modified form of the improvement on same scale as Fig. 2, the cord being shown in position securely clasped by the double hook, a portion of the handle being broken away. Fig. 4 is a section on line A—A of Fig. 3, portions of the hook being broken away. Fig. 5 is a modification, the clasping surface T roughened.

These illustrations show the forms which my invention may take, but I do not wish to be limited to these special constructions as other variations may be used without departing from the spirit of my invention.

Similar letters refer to similar parts throughout the different illustrations.

The metallic package tie and handle B comprise at one end the plain hook of ordinary construction C engaging the cord D and the other end formed into a similar hook E lying parallel to the first but having a double bill F composed of the main part G and the spring clasp H, the peculiar construction and purpose of which will be hereinafter described. Connecting the two across the intervening space and at right

angles to said hooks lies the handle I, which preferably is enveloped in an enlarged casting of any suitable material J shown in dotted lines.

We now have in general outline a widely known and generally used package handle, but which I greatly improve by adding the cord fastener, which I now describe.

The bill of the hook E at its outer and upper extremity is connected by the spring bend K to a second member H of the same general form and lying closely against the main part G. At a point preferably near the throat of the hook E where the main stem M takes an upward direction, I give the spring clasp H, a partial turn on the aforesaid main stem in a more or less spiral form, partially inclosing M but not to an extent that impedes the swinging movement necessary when the cord is inserted between M and H. The extreme end of H as at N is now slightly turned outward for the easy placing of the cord without catching. As can easily be observed when the spring clasp H is forced away from G the opening between the two does not increase as fast at point L as at O where the convolutions Q of cord D and against which the ends P of said cord are intended to lie, therefore the passage being restricted the ends P are retained from slipping out of the grip of the members H and G which go to make up the double bill of hook E. The double hook E formed by the return of H upon the bill G easily receives the convolutions Q of cord D tending to tighten the grip of H and G upon the ends P when drawn into the slot S formed between the two.

In carrying a bundle with a handle placed upon the binding string, it has been found, that, more often than otherwise especially in a medium heavy package, that the handle slips over to one end, making the carrying thereof unhandy and unwield. Recourse is had to giving the handle one or more twists after placing the first hook upon the string. After this is done the second hook is affixed in the usual way. Now in placing the handle, provided with my improvement upon the string and manipulating it as hereinafter described, requires no more time or trouble than the twisting operation, and, moreover, the time of tying a proper knot is eliminated and the handle is held in a central position with no fear of misplacement.

When proceeding to use my improvement,

the package is bound with the cord D in the accustomed manner, and even when completed the two ends P are grasped in one hand. Now with the other hand the package handle B is taken and the carrying hook E having my improved tie is placed upon the two parts near the hand, or at a predetermined distance from the center of the package. Drawing the string tightly across the hook until the required tension is obtained, still retaining carefully the handle with its tie in one hand and the two ends P in the other. The aforesaid ends are now given one or more turns about the double bill F of carrying hook E and placed across the member M above and on the same side as clasp H, then forced downwardly along the side of aforesaid M where the outwardly bent end N of clasp H easily allows the string to take a position between main body M and clasp H. Continuing the movement the ends P of string D reach the extreme of travel in the slot S, and lie against the convolutions Q of string D as at O clearly illustrated in Figs. 2 and 3. The clasp H is now gripping the ends P with its inherent elasticity and further enhanced by the reaction of the tightly wound turns of string D about the double bill F and when force is exerted in lifting by the handle, these convolutions produce a multiplied reaction in direct relation to the power exerted in lifting. The further act of placing

the other hook C upon the string in the usual manner is now performed and the handle with its tie gripping the string is in readiness for use. 35

Having thus described my invention, what I claim as new, and desire to secure by Letters Patent, is—

1. A package carrier handle formed from a piece of spring metal, comprising a U shaped member, a cord receiving member bent upwardly from one end of the U shaped member, a second cord receiving member bent outwardly and upwardly parallel to but spaced from the other end of the U shaped member, said second cord receiving member being then bent downwardly and inwardly to form a cord clamp, a portion thereof being 45 turned partially across the adjacent leg of the U shaped member to form an obstruction. 40

2. A device of the character described comprising a wire member bent back upon itself at one end to provide means for engaging and fastening together the ends of a cord or string about a bundle and having a hook on its other end to engage beneath a portion of said cord remote from the fastened ends, a central portion of said wire being raised to provide a grip for the hand. 55 50
